UNITED STATES PATENT OFFICE

ROY BLAIR EVERSON, OF CHICAGO, ILLINOIS, ASSIGNOR TO THE EVERSON FILTER COMPANY, OF CHICAGO, ILLINOIS, A CORPORATION OF ILLINOIS

CIRCULATING WATER-LEVEL CONTROL

Application filed February 23, 1929. Serial No. 341,949.

This invention is intended primarily for use in association with swimming pools, or display fountains and the like; and the objects of the invention are primarily to provide means for regulating the water level in a pool, during the period of recirculation; which pool in itself is part of a recirculating system such as is now commonly used for the purifying of the water in a swimming pool, and thus permitting the water to be used over again.

At the present time these circulating systems operate under a pressure which is in excess of the water pressure maintained in the city water mains, which mains are the initial source of water supply for the pools, and it has been found that often through carelessness on the part of the operator, the water from the pool has been allowed to back up and enter the city water mains, which is not satisfactory and is condemned by the various boards of health in the larger cities. Therefore, one of the major objects of this invention is to eliminate any possibility of the water in the swimming pool, either before or after it has been purified, from backing up or entering the city water supply through any faulty manipulation of the recirculating equipment.

Another object of this invention is to eliminate the possibility of the sewer backing up, entering, and contaminating the recirculating system.

A further, and a very important object of this invention is to provide means whereby a reserve supply of water is maintained at all times, independent of the water level in the pool, at the same time permitting of the constant and uninterrupted recirculation of the water for the pool.

A still further object of this invention is to make the pool itself an emergency reservoir, and to provide a make-up water tank, or an independent means of storing up and thus equalizing the overflow from the pool, which overflow may be occasioned by a large number of bathers entering the pool at one time; and from this make-up tank providing means for putting this overflow back into

circulation and thus preventing its loss as heretofore.

The accompanying drawing illustrates a portion of the deep end of a swimming pool, and the make-up tank, shown in section; the control system of piping and valves being shown in elevation.

In the description of my invention I have chosen to show the deep end of a standard form of swimming pool in cross section, being designated by the reference character 1. At a point adjacent to, and preferably below the swimming pool, I have provided an open top tank 2, which I shall term a make-up tank, and which make-up tank has its overflow 3, near the top as shown, and drain 4, at the bottom. Through the usual drain 5, preferably located as shown at the deepest point of the pool 1, the water of the pool is conveyed by means of the pipe 6, and valve 9, either directly to the make-up tank 2, or is bypassed through the pipe 7, and valve 10, to the floor drain (not shown) which floor drain connects direct to the sewer; therefore, by means of alternately opening and closing the valves 9 and 10, the water from the pool is drained either directly into the make-up tank or sewer. Where the pipe 6, terminates at the make-up tank, a float valve 6a is provided, which opens when the water level goes below the line 29, and which valve closes when the water level raises above the line 29.

In the wall of the pool, preferably adjacent to the top rim or gutter, is interposed a drain or skimmer fitting 11, which is connected by means of the pipe 12, and valve 12a, to a vertical open top stack 13, which, like the pipe 6, discharges into the make-up tank 2 at a point above the overflow 3.

Where the pipe 13 terminates at the make up tank, a float valve 13a, is provided, which opens when the water level goes below the line 30, and which valve closes when the water level rises above the line 30.

At a point in the pool wall, substantially below the fitting 11, is located another or similar drain fitting 14, which, likewise, is connected by the pipe 15 and valve 16 to the stack 13; branching upwardly from the pipe

15, between the fitting 14 and valve 16 are located a plurality of pipes 17, 18 and 19 which parallel the pipe 15, and in the same manner are provided with valves 20, 21 and 22 just before they enter the stack 13.

10 The initial water supply, preferably from the city water mains, is brought to the make-up tank by means of the pipe 23, and manually operated valve 23a. Where the pipe 23 terminates at a point several inches above the top of the make-up tank, a float valve 24 is provided, which opens when the water level goes below the line 31, and which valve closes when the water level rises above the line 31, or approximates the overflow 3 of the make-up tank.

15 The drain 4, from the make-up tank 2, enters the pipe 4a, and through the valve 25, discharges to the floor, and through the floor drain to the sewer (not shown) or by means of the valve 26, the water from the tank 2, is pumped into the water purifying system (not shown) for recirculation and final discharge into the pool 1.

20 25 In operation, all valves are closed. Open the valve 23a, and 12a. The make-up tank 2, being empty leaves the float valve 24, open on the end of the initial water supply line 23, thus starting to fill this tank to the level indicated as 31. The valve 26 is opened, allowing this fresh or raw water to enter the purifying system (not shown) where it is put under pressure and fed to the swimming pool. When the water level in the pool reaches the point indicated in the pool as 27 it will overflow, or skim as it is termed, back through the fitting 11, pipe 12, and valve 12a into the stack 13 and then into the make-up tank 2. The water level in the make-up tank 30 ultimately reaches the point indicated as 30, at which time the float valve 13a will close, this will allow the water level in the make-up tank to rise to the level indicated at 31, when the float valve 24 will close and prevent any more raw water to enter the system.

40 45 The valve 23a is now closed, thus shutting off all connections with the city water supply.

50 The valve 9, is next opened, but as the water level in the make-up tank is at 31, a point above that level 29, the float valve 6a remains closed.

55 60 Should the water level in the pool rise to a point above that as indicated at 27, with the water level at 31 in the make-up tank, which condition would be occasioned by a large number of bathers entering the pool at one time, the resulting overflow will be retained in the pool and raise the water level in the pool up to its overflow gutter 32, where the water will pass into the main drain of the building and then to the sewer; as the float valve 13a will be closed, the water level in the make-up tank being at 31, and above 65 the level 30.

When this high water level recedes, that is, when the bathers are again out of the pool, the water again seeks the level 27, and due to the continuous drain on the make-up tank occasioned by the recirculating pumps, the water level in the tank recedes to a point below the level 30, thus opening the valve 13a and permitting of the skimming of the pool for recirculation.

70 75 Should there be an abnormal loss of water either overflowing into the gutter or otherwise, and the water level in the make-up tank drop below the minimum level designated at 29, the float valve 6a will open, which insures a water supply for the make up tank as long as there is water in the pool.

80 85 The above provides for recirculation when the pool is maintained at its maximum depth, but often times it becomes desirable to appreciably lower this level, in which case, by opening the valve 16, the lower fitting 14 then becomes the drain or skimmer, and by lowering water level to the point marked 28, still permit of the continued uninterrupted recirculation of the water in the pool.

90 95 It is not desirable to have too many of these fittings in the wall of a pool, therefore I have limited myself to two fittings, as shown and described, representing the maximum and minimum depths required. Should there arise an occasion for varying the depth of the pool to a point between the above extremes, I have provided a plurality of by-passes, whereby upon closing the valve 16, and opening one of the valves 20, 21 or 22, and then lowering the 100 water in the pool to the level of the valve opened, the water in the pool will continue to circulate as before described.

100 105 Having thus described my invention, what I claim as new and desire to secure by Letters Patent is:—

1. In a water circulating system for swimming pools including an overflow gutter, a make-up water tank in piped communication with the pool from a point below and independent of said overflow gutter, the top or maximum water level of said make-up water tank being below the lowermost water level of said pool.

110 115 2. In a water circulating system for swimming pools including an overflow gutter, a make-up water tank in piped communication with the drain of the pool and also from an additional point below and independent of said overflow gutter, the top or maximum water level of said make-up water tank being below the lowermost water level of said pool.

120 125 3. In a water circulating system for swimming pools including an overflow gutter, a make-up water tank in piped communication with the drain of the pool and also from two points below and independent of said overflow gutter, the top or maximum water level of said make-up water tank being below the lowermost water level of said pool.

4. In a water circulating system for swimming pools including an overflow gutter, a make-up water tank in piped communication with the drain in the bottom of the pool and 5 also from a point below and independent of said overflow gutter, the top or maximum water level of said make-up water tank being below the lowermost water level of said pool.

5. In a water circulating system for swimming pools including an overflow gutter and 10 a drain, a plurality of skimmer fittings mounted in the vertical walls of said pool and interposed between said drain and gutter a make-up water tank in piped communication 15 with said skimmer fittings and said drain means for controlling the flow of water from the pool to said make-up water tank.

6. In a water circulating system for swimming pools including an overflow gutter and 20 a drain, a plurality of skimmer fittings interposed between said drain and gutter in the walls of the said pool, a make-up water tank in piped communication with said skimmer fittings and said drain, automatic means for 25 controlling the flow of water from the pool to said make-up water tank.

7. In a water circulating system for swimming pools including an overflow gutter and drain, a skimmer fitting interposed between 30 said drain and gutter, an auxiliary skimmer fitting placed between said last mentioned skimmer fitting and said drain, a make-up water tank in piped communication with said skimmer fittings and said drain, and means 35 for controlling the flow of water from the pool to the make-up water tank.

8. In a water circulating system for swimming pools including an overflow gutter and drain, a skimmer fitting interposed between 40 said drain and gutter, an auxiliary skimmer fitting placed between said last mentioned skimmer fitting and said drain, a make-up water tank in independent piped communication with each of said skimmer fittings and 45 said drain, and means for controlling the flow of water from said pool to the make-up water tank.

9. In a water circulating system for swimming pools including an overflow gutter and 50 drain, a skimmer fitting interposed between said drain and gutter, an auxiliary skimmer fitting placed between said last mentioned skimmer fitting and said drain, a make-up water tank in independent piped communication 55 with each of said skimmer fittings and said drain, and means for automatically controlling the flow of water from said pool to the make-up water tank.

10. A water level regulating system for 60 swimming pools including an overflow gutter at the top edge of the pool, comprising a drain fitting in the bottom of the pool, a skimmer fitting interposed between said drain and gutter in the wall of said pool, an 65 auxiliary skimmer fitting placed between

said last mentioned skimmer fitting and said drain, a make-up water tank in independent piped communication with each of said skimmer fittings, means for automatically controlling the flow of water from said skimmer 70 fittings to the make-up water tank, and a plurality of valved pipe communications between said skimmer fitting and said make-up water tank, whereby the circulating water level in the pool may be manually controlled. 75
